(57) **CLAIM**

The ornamental design for a weighted rod for pergola covers, outdoor curtains, or shade panels, as shown and described.

DESCRIPTION

FIG. 1 is a perspective view of a weighted rod for pergola covers, outdoor curtains, or shade panels showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an exploded view thereof.

The drawings contain a symbolic break. The portion between the break lines forms no part of the claimed design.
